GARMENT

Rhoda Jansson, St. Louis, Mo., assignor to Rice-Stix Dry Goods Company, St. Louis, Mo., a corporation of Missouri

Application July 25, 1941, Serial No. 404,055

3 Claims. (Cl. 2—115)

This invention relates to improvements in garments. More particularly, the invention relates to improvements in methods of making garments.

It is an object of the present invention to provide an improved method of making garments.

The method of making garments that is now in general use, consists of forming a sleeve that has a longitudinal seam on the under side thereof, and sewing the sleeve to the bodice. The sewing of the sleeve to the bodice forms an under-arm seam that is transverse to the sleeve. Garments that are made in this manner are satisfactory for most purposes, but in certain instances, they are not completely satisfactory. Where the garments are used by athletically inclined persons, the seam under the armpit is rather irksome. It often partially restricts free movement of the wearer's arm. In addition, the seam is constantly subjected to excessive perspiration emitted by the wearer's pores and gradually weakens. Eventually, the wearer disposes of the garment because of the irksome under-arm seam or disposes of the garment because of the splitting of the seam. For these reasons the present day garments, and the methods of making the garments are not completely satisfactory. The present invention provides a novel method of making garments that is much more satisfactory than present day methods. The invention utilizes the strength provided by the longitudinal seam in the present day sleeve, but in addition, obviates the objectionable under-arm seam and provides a novel method of attaching the sleeve to the bodice of the garment. It is, therefore, an object of the present invention to provide an improved method of making garments that utilizes the strength of longitudinal sleeve seams, and obviates the under-arm seam.

Perspiration has deleterious action on the portions of a garment under the armpit. The action oftentimes results in the weakening of that portion of the garment when the rest of the garment is still quite strong. This is quite objectionable since it materially shortens the life of the garment. The invention obviates this objection by providing a garment having an under-arm portion that is resistant to the attacks of perspiration. It is, therefore, an object of the present invention to provide an improved garment having an under-arm portion that is resistant to the attacks of perspiration.

Other objects and advantages of the invention will appear from the drawings and accompanying description.

In the drawings and accompanying descrip-

tion, preferred embodiments of the invention are shown and described, but it is to be understood that the drawings and accompanying description do not limit the invention, and the invention will be defined by the appended claims.

In the drawings Fig. 1 is a front elevational view of a portion of the bodice of a dress that is made in accordance with the principles of the invention.

10 Fig. 2 is a front elevational view of the sleeve used in the invention.

Fig. 3 is a front elevational view of another portion of the bodice of a dress that is made in accordance with the principles of the invention.

15 Fig. 4 is a front elevational view of a portion of the dress.

Fig. 5 is a front elevational view of the portion of the dress shown in Fig. 4 after it has been turned inside out.

20 Fig. 6 is a front elevational view of a portion of a modified form of dress.

Fig. 7 is a front elevational view of a portion of another modified form of dress.

25 Fig. 8 is a front elevational view of a portion of still another modified form of dress, and

Fig. 9 is a front elevational view of an oiled silk insert used in the dress shown in Fig. 8.

30 Referred to the drawings in detail, a portion of the bodice of a dress made in accordance with the principles of the invention is denoted by the numeral 10. This portion of the bodice has an extension A that is integral with that part of the material that forms the arm hole in the bodice. The numeral 12 denotes a sleeve that may be used with the dress provided by the invention. The sleeve is provided with a pair of extensions B that are integral with the sleeve. When the sleeve is folded and seamed along its sides 14, the extensions B are seamed together to form a semi-elliptical projection B—B. The semi-elliptical projection B—B has a longitudinal seam but does not have the usual transverse under-arm seam. The numeral 16 denotes another portion of the bodice of the dress. The portion 16 also has an extension A that is integral with that part of the material that forms the arm hole in the bodice. When the edge 18 of portion 10 and the edge 18 of portion 16 are seamed together, a semi-elliptical projection A—A is formed. This semi-elliptical projection A—A has a longitudinal seam but does not have the usual transverse under-arm seam. To complete the garment, the projection B—B is inserted into the arm hole formed by the joining of portions 10 and 16. The edge of the projection B—B is sewed directly to the bodice and extends

a distance below the armpit. The edge of projection A—A of the bodice is then sewed directly onto the under side of sleeve 12, and extends a distance out from the armpit. This arrangement obviates the usual transverse under-seam with its attendant disadvantages and objections. Wherever, in the drawings, one of the semi-elliptical projections A—A or B—B is shown, behind the material forming the sleeve or the bodice, the projection is denoted by dotted letters.

In Fig. 6 a modified form of garment is shown. This garment has all the structural features of the garment shown in Figs. 4 and 5, and is additionally provided with eyelets 20 in double section. These eyelets provide ventilation for the armpit and materially aid in reducing under-arm perspiration. By reducing the amount of perspiration, the eyelets lengthen the life of the garment.

Fig. 7 shows a garment having all the structural features of the garment shown in Figs. 4 and 5. This garment is additionally provided with a plurality of rows of stitching. The stitches extend through the sleeve and the bodice and securely attaches the two portions together. The rows of stitching form geometrically similar ellipses of various sizes that extend over the area formed by the projections A—A and B—B. The rows of stitching are used on garments that are designed for persons engaging in particularly strenuous activities. The rows of stitching cooperate with the transverse seams of the sleeve and bodice to make a very strong under-arm connection between the sleeve and the bodice.

In Fig. 8, a garment is shown that has all the structural features of the garment shown in Figs. 4 and 5. This garment has the additional feature of an insert of oiled silk positioned between the semi-elliptical projections A—A and B—B. This insert of oiled silk is shown in Fig. 9 and is indicated by dotted lines in Fig. 8. This insert positively protects the projection A—A from the action of perspiration and prevents the weakening thereof. In addition, the insert obviates the dampness of the material under the armpit that is rather unsightly.

The drawing and accompanying description have shown and described preferred embodiments of the invention, but it is obvious to those skilled in the art that various changes in form may be made without changing the scope of the invention.

What I claim is:

1. An improved garment comprising a bodice having a pair of armholes and a pair of semi-elliptical projections, said semi-elliptical projections extending from and being integral with the material forming the lower portion of the armholes, a pair of sleeves that each has a longitudinal seam on the under side thereof and a semi-elliptical projection on one end thereof that is integral with the material of which the sleeve is made, said semi-elliptical projection on each of the sleeves having a longitudinal seam therein but having no transverse seam therein, said semi-elliptical projection on each of the sleeves being substantially similar to the corresponding semi-elliptical projection on the bodice, a pair of pock-

ets formed by sewing the edge of the semi-elliptical projection on each of the sleeves directly to the material of the bodice below the armhole and sewing the edge of each of the semi-elliptical projections of the bodice to the under side of the adjoining sleeve, a pair of elliptical inserts of oiled silk that are positioned in the said pockets and are adapted to protect the outer portion of each of the said pockets from the action of under-arm perspiration, said pockets having longitudinal seams therein but having no transverse under-arm seam.

2. An improved garment comprising a bodice having a pair of armholes and a pair of semi-elliptical projections, said semi-elliptical projections extending from and being integral with the material forming the lower portion of the armhole, a pair of sleeves that each has a longitudinal seam on the under side thereof and a semi-elliptical projection on one end thereof that is integral with the material of which the sleeve is made, said semi-elliptical projection on each of the sleeves having a longitudinal seam therein, said semi-elliptical projection on each of the sleeves being substantially similar to the corresponding semi-elliptical projection on the bodice, each of the sleeves being associated with the bodice of the garment in such a manner that the semi-elliptical projection on each sleeve directly engages the material of the bodice below the adjoining armhole and the corresponding semi-elliptical projection of the bodice directly engages the under side of the adjoining sleeve, and a plurality of rows of stitches that are arranged to form a plurality of geometrically similar ellipses, said geometrically similar ellipses extending over the area formed by the semi-elliptical projection on a sleeve and the corresponding semi-elliptical projection on the bodice, said rows of stitches extending through the material of the bodice and the material of the sleeves and serving to materially strengthen the under-arm portions of the garment without utilizing a transverse seam.

3. An improved garment comprising a bodice having a pair of arm holes and a pair of outwardly extending projections, said projections extending from and being integral with the material forming the lower portion of the arm holes, and a pair of sleeves that each has an outwardly extending projection on one end thereof that is integral with the material of which the sleeves is made, said outwardly extending projections on each of the sleeves being substantially similar to the corresponding outwardly extending projection on the bodice, a pair of pockets formed by sewing the edge of the outwardly extending projection on each of the sleeves directly to the material of the bodice below the arm hole and sewing the edge of the outwardly extending projections of the bodice to the under side of the adjoining sleeve, a pair of inserts of substantially non-absorbent material that are positioned in the said pockets and are adapted to protect the outer portion of each of the said pockets from the action of under-arm perspiration.
